UNITED STATES PATENT OFFICE.

WILLIAM HUNTER, OF BLACKPOOL, ENGLAND.

FORCE-PUMP FOR LIQUIDS.

1,362,315.

Specification of Letters Patent. Patented Dec. 14, 1920.

Application filed March 9, 1920. Serial No. 364,489.

To all whom it may concern:

Be it known that I, WILLIAM HUNTER, a subject of the King of Great Britain, residing at Blackpool, in the county of Lancaster and Kingdom of England, have invented a certain new and useful Improved Force-Pump for Liquids, of which the following is a specification.

This invention relates to an improved pump for liquids of the type in which an outer cylindrical member having suction and delivery ports co-operates with an inner cylinder having suction and delivery ports and with an innermost piston.

15 The object of the invention is to provide an arrangement which will be particularly applicable as a force pump for liquids by which it will be possible to obtain high pressures by an extremely simple apparatus, and 20 it is a particular object of the invention to reduce the number of the parts necessary for the construction of a simple pump. It is a further object of the invention to overcome the liability for liquid to leak out of the 25 chamber within the inner cylinder during the movement of said cylinder from one registering position to another. It is also an object of the invention to provide a pump in which sharp clearance can be obtained 30 so that the suction and delivery ports are open full bore as long as possible.

To these and other ends, it will be apparent from the description, the invention comprises the combination of parts which will 35 be understood from the following description of an illustrative example, and the scope of which will be defined in the appended claims.

In these drawings:—

40 Figure 1 is a half sectional elevation (side view).

Fig. 2 is a front elevation of the pump.

In these drawings, 1 is the outermost cylinder or casing provided with a suction port 45 2 and a delivery port 3 communicating through suitable threaded connections with a delivery pipe 4. These parts may be mounted within a container 5 which may contain the oil, although this may also be 50 supplied in other ways to the suction opening.

Within the casing 1 there is an inner cylinder 6 provided with an enlarged head 7 and having a suction port 8 and a delivery port

55 9. This cylinder is open-ended at the bottom and it contains a false piston 10 which

is very accurately machined to fit within the cylinder. This false piston 10 projects through the base 11 mounted within the container 5. This base plate 11 has also 60 mounted thereon a flanged piece 12 and the outer cylinder 1, but the arrangement is such that air can be admitted beneath the bottom of the cylinder 6 when it rises about the false piston 10; the fit between the false 65 piston 10 and the cylinder 6 is so close that no substantial escape of oil can take place. Within the cylinder 6 there is mounted a tightly fitting piston 13.

The piston and inner cylinder are reciprocated by suitable mechanism of which a specific illustration is shown in the drawings and will be described later, in such manner as to perform the following series of operations:—

70 1. While the opening 8 registers with the opening 2, the piston 13 is caused to rise and suck in a charge of oil. During this time, it is preferable that the cylinder 6 shall be caused to dwell so as to maintain the ports 80 2 and 8 in full bore engagement, but this is not absolutely essential, particularly in cases when there is very little clearance between the inlet and outlet ports of the cylinder so that the whole travel of the cylinder 85 is slight in comparison with the size of the ports.

2. In the second position, the piston is caused to dwell and the cylinder moves downward into the position shown in Fig. 90 1. During this movement, as the piston 13 is caused to dwell and as the false piston 10 is stationary, there is no tendency to compression or expansion of the oil contained in the space between the piston and false piston 95

as would be the case if the cylinder were employed with a closed end as has been proposed hitherto. If such a cylinder is employed having a closed end, it will be clear that either the apparatus will be inoperative, or that leakage must take place either inward or outward at a time when the piston is stationary and when neither of the ports 8 and 9 is in engagement with the ports 2 and 3. The false piston 10 is an important fea- 100 105

ture of my invention since it enables these difficulties to be overcome by allowing movement of the cylinder without causing compression or expansion of the oil contained therein.

110 3. When the port 9 registers with the port 3, the cylinder is then preferably caused to

dwell and the piston 13 is forced downward thus discharging the oil through port 3 and pipe 4. Fig. 1 shows the piston near the bottom of its downward stroke.

5 4. The piston is then caused to dwell and the cylinder 6 is moved upward till port 8 registers with port 2.

10 It will be seen that by providing a dwell in the movement of the cylinder and piston, it is possible to avoid leakage. This object can be obtained by providing a dwell in the movement of the piston alone, but in addition it is also preferable to cause the cylinder to dwell in order to secure full bore engagement of the ports as above described.

15 In practice, I find that the above operations can be obtained in the most simple and positive manner by employing rollers engaging cam grooves on opposite sides of 20 the same cam disk, and this arrangement has the advantage of great simplicity, so that only few parts are required which can be assembled very rapidly indeed. From the above description, it will be seen that each 25 cam groove should have two opposite quarters concentric to allow for the dwell periods and two opposite quarters eccentric to provide for the upward and downward movements, and further one cam groove should 30 lead the other by one quarter of the revolution. In Fig. 1, the dotted lines show the cam groove 14 within which is arranged a roller 15 attached to the piston. The full lines show the cam groove 16 within which 35 is mounted the roller 17 connected with the flanged head 7. It will be seen that these 40 grooves are on opposite sides of the cam disk 18 which is mounted on a square shaft 19 journaled at 20 and 21 within the casing 5. 45 This shaft may be rotated mechanically or by means of a hand wheel 22 having a handle 23 and ratchet teeth engaging with a pawl 24. The roller 15 is mounted on a head 27 at the top of the piston 13 while the roller 17 is carried on a bracket 28 projecting upward from the flange 7.

50 25 is a pin projecting downward from the flange 7 to engage with a vertical groove 26 on the casing 1 in order to prevent relative rotation between the inner and outer cylinders.

55 It will be seen therefore that a valveless pump, especially valuable as a force pump, has been provided having means to maintain a constant volume of liquid in the inner cylinder beneath the piston 13, while this cylinder is moving from registry between the

inlet ports to registry between the outlet ports.

I declare that what I claim is:—

1. A pump having a ported outer cylinder, a ported open-ended inner cylinder having a substantial clearance between inlet and outlet registry of said ports and an innermost piston in combination with a false piston within the inner cylinder and means to reciprocate the innermost piston allowing a dwell while the inner cylinder is moving. 60

2. A pump having a ported outer cylinder, a ported open-ended inner cylinder having a substantial clearance between inlet and outlet registry of said ports and an innermost piston in combination with means to maintain a constant volume of liquid in the inner cylinder while the cylinder is moving from registry between inlet ports to registry 75 between outlet ports.

3. A pump having a ported outer cylinder, a ported open-ended inner cylinder and an innermost piston in combination with a false piston within the inner cylinder, means to reciprocate said cylinder and means to reciprocate the innermost piston allowing a dwell while the inner cylinder is moving. 80

4. A pump having a ported outer cylinder, a ported open-ended inner cylinder and an innermost piston in combination with a false piston within the inner cylinder and means to reciprocate the inner cylinder and innermost piston in such manner that the piston dwells while the cylinder is moving, and 90 vice versa.

5. A pump having a ported outer cylinder, a ported open-ended inner cylinder and an innermost piston in combination with rollers 95 engaging in cam grooves on opposite sides of a cam disk to reciprocate the inner cylinder and the piston.

6. A pump having a ported outer cylinder, a ported open-ended inner cylinder, and an innermost piston in combination with a false piston within the inner cylinder and means to reciprocate the innermost piston including cam means so arranged that a concentric movement of the cam takes place while the inner cylinder is moving. 100

105 In witness whereof I have hereunto signed my name this 16th day of February, 1920, in the presence of two subscribing witnesses.

WILLIAM HUNTER.
